DANCING FIGURE TOY

Anthony Scampoli, 317 E. 4th St.,
Mount Vernon, N.Y. 10553

Filed Jan. 20, 1971, Ser. No. 108,242

Term of patent 14 years

Int. Cl. D21—01

U.S. Cl. D34—15

FIG. 2

FIG. 1 is a perspective view of a dancing figure toy embodying my new design;

FIG. 2 is a front elevational view thereof;

FIG. 3 is a top plan view thereof; and,

FIG. 4 is a side elevational view thereof, the opposite side being similar.

The legs of the figures are shown in various exemplary positions in the views.

I claim:

The ornamental design for a dancing figure toy, as shown and described.
